UNITED STATES PATENT OFFICE

1,926,814

APPARATUS FOR KNITTING SEAMLESS STOCKINGS

Georg Nobst and Ernst Ulbricht, Mittweida, Germany, assignors, by direct and mesne assignments, to Scott & Williams Incorporated, New York, N. Y., a corporation of Massachusetts

Application January 26, 1928, Serial No. 249,631,
and in Germany January 27, 1927

6 Claims. (Cl. 66—14)

This invention relates to method and apparatus for the manufacture of tubular fabric such as seamless stockings, and more particularly to the formation of heel and toe pockets in such tubular fabric. The invention is applicable to flat knitting machines having two beds, as well as to circular knitting machines, but it will be shown and described embodied in a circular knitting machine.

10 In making the heel and toe pockets of seamless stockings it is customary to knit the partial courses by a to-and-fro or reciprocating movement, and the average speed of this reciprocation is necessarily lower than the speed of round-and-round knitting. According to the present invention the heel and toe pockets, as well as all other parts of the stocking, are made by round-and-round knitting.

In the drawings:

20 Fig. 1 is a representation of one form of sock knit in accordance with the present invention;

Fig. 2 is a development of the interior of a cam cylinder illustrating the position of the parts, for knitting the stocking shown in Fig. 1, during the 25 knitting of complete courses;

Fig. 3 is a development similar to Fig. 2 showing the position of the parts when knitting partial courses in round-and-round knitting;

Fig. 4 is a vertical radial section;

30 Fig. 5 is a cam development of a machine having superposed concentric cylinders and using double ended needles;

Fig. 5a is a composite diagrammatic section through the cam cylinder substantially on the 35 lines A—A, B—B and D—D respectively of Fig. 5;

Fig. 6 is a set of diagrams respectively showing successive operations in making a stocking leg, heel, and foot;

Fig. 7 is a corresponding view of the product in 40 two stages corresponding to Fig. 6;

Fig. 8 is an elevation illustrating the fabric resulting from the method of knitting herein described and showing the gap at the side of the heel before the gap has been closed; and

45 Fig. 9 is a view similar to Fig. 8 after the gap has been closed.

For purposes of illustration the invention will be shown embodied in a circular purl knitting machine of the revolving cam cylinder type, such, for instance, as shown and described in our pending application for United States patent Serial No. 223,135, filed September 15, 1927, [Patent No. 1,720,606, July 9, 1929] and our applications for United States patent executed of even date here-with, Serial No. 249,629 "Pattern forming mech-

anism for circular knitting machines" and Serial No. 249,630, "Control mechanism for circular knitting machines". This type of machine has double ended needles and two-part sliders for said needles. We will first describe the method and apparatus for producing the stocking shown in Fig. 1, which involves the use of a selector wheel such as shown in Figs. 2 and 3. Thereafter we will describe the manufacture of the ordinary type of narrowed and widened seamless heel pocket by the use of the type of pneumatic jacquard control which forms the subject matter of the above mentioned application, Serial No. 249,629, "Pattern forming mechanism for circular knitting machines".

Referring now to Figs. 2 and 3 of the drawings, the revolving cam cylinder 40 is provided with a cam ring 42 defining a channel or path 47,—hereinafter referred to as the idle path,—and a separate working path 48 positioned above the idle path. The butts 50 of the needles, or of their actuating jacks—or in the case of a purl machine, needle actuating sliders—move in these paths and are indicated in the drawings by the reference number 50. The butts move to the left as they appear in the drawings. There is the usual knitting cam 51 interposed in the paths 47 and 48 under whose tip 52 all the butts must pass. The two paths 47 and 48 converge in advance of the knitting cam to form a single path and immediately behind the knitting cam, i. e., to the left as shown in the drawings, the two paths separate once more. To determine into which path the butts will flow after passing the point 52 of the knitting cam, there is a switch cam 54 pivotally mounted in the cam cylinder, so located that when swung upwardly, as shown in Fig. 2, it will close the idle path and force the butts into the working path 48. When swung downwardly the butts will go into the idle path 47, as shown in Fig. 3. This switch cam may be controlled in any usual manner.

Machines of this type knit a very long stitch, and by reference to Patent No. 1,720,606 above referred to it may be seen that there is a large 100 clearance between the butt of the lower pusher jack and the top and bottom walls of the recess in the rocker jack. Thus when the rocker jack rises to the lower cam groove 47, after drawing the stitch, the needle is not raised to an equal amount by reason of the lost motion between the parts, so that the hook of the needle (when the rocker jack butt engages the idle groove 47) is below the 105 yarn taking point and thus the needle continues to hold its previous stitch until its rocker jack is 110

elevated by the pattern wheel. To those skilled in the art a proper location of the yarn feed guide will be obvious to obtain this desired result, one such point being indicated, for example, at F in Fig. 5, it being noted that it is not necessary to retract the hooks of the idle needles wholly below the cylinder verge in order to prevent them from taking the yarn, such an arrangement being well known in the art as shown for example in the 10 patent to Hirner, No. 1,062,910. Moreover, if the machine is to be employed solely for knitting tubular stockings having the improved heel and toe construction as shown in Fig. 1, it is obvious that the upper cylinder may be dispensed with 15 entirely as illustrated in Figs. 2 and 3 and that in that event the position of the yarn feed guide may be varied within wide limits as will be obvious to those skilled in the art since the hooks of needles elevated by the selector wheel are at a 20 very substantial distance above the hooks of needles moving in the idle path.

For the purpose of raising half of the butts to the working path 48 when it is desired to begin formation of a heel or toe pocket, a toothed selector wheel 43 is provided. This selector wheel rotates at a diagonal or oblique relation to the cam cylinder, such that its circumference reaches from the lower path 47 to the upper path 48, the wheel being mounted in a slot 46 in the cam cylinder 40. 25 The two cam paths are connected at this point by a groove 49 in which the butts ride when raised by the wheel. This selector wheel may be of any usual construction, but it is shown and described with teeth arranged vertically with relation to the cam cylinder and forming notches therebetween which correspond in number with the number of needles in the needle cylinder. This pattern wheel is shown and described in detail in the 30 above mentioned application for United States patent, Serial No. 249,630 for "Control mechanism for circular knitting machines". In carrying out the method of the present invention by means of the use of this selector wheel, slugs or fillers 45 are placed in the bottom of the slots 35 around one half the periphery of the wheel and the other slots are left open. It will be obvious that when a butt comes in contact with the slot containing such a slug, the continued rotation of the cam cylinder will cause the butt to be pushed 40 upwardly into the working path 48, while if the butt registers with a slot open at the bottom, it will turn the wheel but will itself remain in the lower or idle path 47. The wheel is therefore 45 adapted when partially filled with slugs, as above described, to raise half the butts to the working path and leave the other half in the idle path and this separation is availed of in making a heel or toe pocket according to the method now being 50 described.

According to this method the leg portion *a* of the stocking is knit with complete round-and-round courses while the switch cam 54 is raised to the position shown in Fig. 2. The pattern wheel may be retired from contact with the butts, 55 by any usual mechanism such for instance as that shown in the United States patent to Hirner 1,026,206 dated May 14, 1912. This retirement, however, is not necessary to the carrying out of our method. When the switch cam thus keeps 60 all the butts in the working path 48, all the needles are in active operation and the leg is knit in the usual manner. When the instep *b* is reached the machine does not change to reciprocatory knitting, as heretofore, but continues its round-and-round movement at the high speed which is

possible for round-and-round knitting and the switch cam 54 is thrown down out of action as shown in Fig. 3. The butts of the needles, jacks or sliders, as the case may be, as they come from under the point 52 of the knitting cam 51 will then go into the idle path 47 and passing along in that path will encounter the selector wheel 43. The half of the needles which register with slots having slugs 45 therein will thereupon cause the pattern wheel to raise them to the working path 48 in which position the needles in the needle cylinder will receive yarn for new stitches. The needles which register with open slots turn the pattern wheel, and remaining in the idle slot 47 hold the loops last drawn thereon. This selection of half of the knitting instrumentalities by the pattern wheel, continues for a number of courses (for example, Fig. 7, from the course *a*, *b*, *k*, where knitting was suspended, to form the heel strip *b*, *d*, *e*, *h*, *g*, *k*) until sufficient fabric for the heel has been knit, the yarn being floated across from one end of the active segment of needles to the other at each course, as shown at II, Fig. 6. It will be noted that the stitches thus knit by the end needles of this active segment during the 100 knitting of these partial courses, are not inter-looped in any way with the stitches held on the inactive semi-circle of needles and short gaps *b*, *d*, *e*, *h* are therefore formed at each side of the heel. The edges of these gaps may be stitched 105 together in any desired manner after the completion of the stocking as shown at *c*, Figs. 1 and 9, for example. After the completion of the instep portion *b* of the heel the switch cam 54 again closes the idle path 47, and all the butts are raised 110 to the active path 48, whereupon the knitting of complete courses is resumed, forming the foot. The toe pocket is formed in exactly the same manner as the heel pocket, the knitting of complete courses being resumed after the formation 115 of sufficient fabric for the toe, and thereafter sufficient complete courses are knit to complete a stocking of the desired size, and to provide extra courses before knitting the neat stocking,—the stockings being knit in integral succession to each 120 other.

Our method of knitting the heel and toe pockets during round-and-round knitting of partial courses, can be carried out to make the usual narrowed and widened seamless heel or toe pocket 125 when a Jacquard type of control is used. One example of such a control is the pneumatic control forming the subject matter of our application for United States patent, Serial No. 249,629, filed January 26, 1928, "Pattern forming mechanism for circular knitting machines". In following out this method holes are punched in the Jacquard card wherever and whenever it is desired that the needle should knit, and it will be 130 obvious that by progressively changing the number of holes the active segment of needles can be progressively decreased and then increased. It will be observed that by the use of the Jacquard type of control in connection with our method it is possible to progressively narrow and widen 135 the active segment of needles during round-and-round knitting, not only at the leading end of the active segment but also at the following or rear end of the segment.

Referring to the drawings, the circular purl 145 knitting machine illustrated includes a lower needle cylinder *r* and an upper needle cylinder *u* superposed thereon and suitable cam cylinders with provision for relative movement of rotation between said needle and cam cylinders, the 150

cam cylinder as shown being the rotatory element. Double ended needles *e* are arranged to slide longitudinally in the aligned tracks of said cylinders and their movement is controlled by means of 5 suitable jacks or sliders each comprising a pusher *s* and a hook, as *f* and *f'*; said hooks being provided with butts 150 and 151 respectively. A cam cylinder 40 encircles the needle cylinders *r* and *u* and includes a lower cam ring 42, defining a path 10 adapted to coact with the hook butts in the lower cylinder *r* and an upper cam ring 41 defining a path adapted to coact with hook butts in the upper cylinder *u*. In the form of device illustrated in Figs. 4 and 5, the lower cam ring 42 is 15 provided with separate butt engaging and guiding paths which converge adjacent to the working face of a knitting cam 51 and form around the end of said cam a single path.

As indicated in Fig. 4, the upper end of each 20 hook *f'* is provided with a slot or recess *w* adapted to receive and retain one end of the harness thread forming part of a jacquard mechanism more fully described in our said application Serial No. 249,629, filed January 26, 1928.

25 As illustrated in Fig. 5, and as more fully described in our Patent No. 1,720,606, we provide the adjustable switch cam *v*, which under normal circumstances is aligned with the bottom of the cam groove 47, but which may be raised to inclined position.

Referring to Fig. 5^a, the cam rings which define the groove 47 comprise spaced portions 1 and 2, while the cam rings which define the groove 47' comprise spaced portions 3 and 4, and these 35 parts 1 and 2, and 3 and 4 are so shaped as to rock the jacks, or at least the retracting portions of the jacks, in and out, toward and from the needle cylinders. Thus throughout the main portion of the circumference of the cam cylinder (Fig. 5^a, Section D) the cam element 1 above the groove 47 and the cam element 3 below the groove 47' have inclined or beveled faces, as also indicated at the left side of Fig. 4, which permit the hook ends of the jacks to swing outwardly away from the needle cylinder. At the same portions of the cam cylinder the cam elements 2 and 4 which engage the tails of the jacks are of substantially rectangular cross section in any radial plane, as shown at the left-hand side 40 of Fig. 4 so as positively to maintain the jacks rocked on their pivot points into inoperative position, that is to say, with their hook ends outwardly away from the needles. However, at about the radial plane indicated by the line A—A 45 (Fig. 5) the element 1 in the lower part of the cam cylinder merges into a portion 1^a which is substantially rectangular, while the element 2 merges into a portion 2^a which is beveled or inclined. As a jack of the lower series passes the 50 plane A, the cam elements 1^a and 2^a swing the jack so that its head moves radially inward to a position to engage the hooks of a needle properly positioned to receive it.

On the other hand, the cam element 3 of the 55 upper portion of the cam cylinder at substantially the plane B—B which is ahead of the plane A—A, merges into a part 3^a of rectangular section (Fig. 5, Section B—B), while the cam element 4 at the same plane merges into a part 4^a of beveled or inclined section. Thus as the jacks of the upper series pass the plane B—B, their heads or hook portions begin to swing inwardly into a position to engage the hook of a needle, but since the plane B—B is in advance of the 60 plane A—A in the direction of rotation of the

cam cylinder, the jacks of the upper series are, under ordinary circumstances, swung into operative position before those of the lower series and thus needles engaged by the upper jacks are moved by the upper jack actuating cam 51 and 65 carried out of the range of the hooks of the lower jacks as the latter are swung inwardly at the plane A—A.

We claim:

1. Mechanism for controlling the actuating butts of knitting instrumentalities in hosiery knitting machines, comprising a cam cylinder having a stitch cam therein and separate butt engaging paths converging in advance of the stitch cam to form a single path whereby said cam retracts the actuating butts of all of the needles, one of said paths being a working path and the other an idle path, said latter path being so arranged that needles controlled by butts disposed therein fail to receive a fresh yarn in 85 their hooks at the feeding point, in combination with means mounted on the cam cylinder for selectively engaging the same segment of the butts in one of said paths and moving them into the other path at each course of successive courses. 90

2. A circular hosiery knitting machine provided with a cam cylinder having a stitch cam therein and separate paths adapted to guide the actuating butts of knitting instrumentalities, one of said paths being a working path and the other 105 an idle path, said latter path being so arranged that needles controlled by butts disposed therein fail to receive a fresh yarn in their hooks at the feeding point, said paths converging into a single path in advance of the stitch cam arranged 110 to guide the butts into effective contact with the stitch cam, whereby said cam retracts the actuating butts of all of the knitting instrumentalities, means mounted in said cylinder for selectively engaging a segment of the butts of heel and 115 toe knitting instrumentalities for moving them from the idle path to the working path at each course of successive courses, in combination with a movable cam located on the opposite side of the stitch cam from said selective means and 120 adapted in one of its positions to close the entrance to one of said paths.

3. Needle actuating mechanism for use in making tubular hosiery on a circular machine having 125 needles and at least one actuating butt for each needle, comprising a stitch cam, a cam cylinder having separate butt engaging paths which converge to form a single path at a point in advance of the stitch cam so that said cam acts to retract the actuating butts of all of the needles, one 130 of said paths being a working path and the other an idle path, said latter path being so arranged that needles controlled by butts disposed therein fail to receive a fresh yarn in their hooks at the 135 feeding point, means, at one side of the stitch cam, operative repeatedly at successive courses for selectively moving a segment of the series of butts from the idle path into the working path and means at the other side of said cam for moving all butts out of said single path and into one 140 or the other of said converging paths at will.

4. A circular hosiery knitting machine of the kind having knitting instrumentalities provided with actuating butts and in which the relative movement of rotation of the knitting instrumentalities and their actuating cams is always in the same direction, said machine comprising a cam cylinder, a stitch cam therein and separate paths 145 adapted to guide the butts of knitting instrumentalities, one of said paths being a working 150

path and the other an idle path, said latter path being so arranged that needles controlled by butts disposed therein fail to receive a fresh yarn at the feeding point, said paths converging into a 5 single path in advance of the stitch cam arranged to guide the butts into effective engagement with the stitch cam whereby said cam retracts the actuating butts of all of the knitting instrumentalities, and means including pattern controlled devices 10 for determining the number of needles to be moved in the working path to form stitches during each course of heel and toe knitting.

5. A circular hosiery knitting machine of the kind having a series of independent knitting instrumentalities provided with actuating butts and in which the relative movement of rotation of the knitting instrumentalities and their actuating cams is always in the same direction, said machine comprising a cam cylinder, a stitch cam 20 therein and separate paths adapted to guide the butts of knitting instrumentalities, one of said paths being a working path and the other an idle path, said latter path being so arranged that needles controlled by butts disposed therein fail to receive a fresh yarn at the feeding point, said paths converging into a single path in advance 25 of the stitch cam and adapted to guide the butts

into effective engagement with the stitch cam, whereby said cam operates to retract the actuating butts of all of the knitting instrumentalities, and means including pattern controlled devices for determining the number of needles entering 80 the working path to form stitches during each course of heel and toe knitting.

6. A circular independent needle hosiery machine of the class described, having needle jacks and needles, and means for moving the needles and jacks successively past a yarn feeding point, cam means comprising a cam ring having therein a single stitch cam for moving the jacks to cause their needles individually to form loops, means to throw the instep segment of needles out of action during the formation of a single course of loops while retaining their loops and for continuing to knit round-and-round on all of the needles of the remaining segment to form a section of fabric of substantially uniform width for a heel pocket, and means for restoring the instep segment of needles to action during the formation of a single course of loops and for thereafter continuing round-and-round knitting.
